UNITED STATES PATENT OFFICE

WALTER LIGHT BODMAN, OF NEW YORK, N. Y., ASSIGNOR TO THE INSULATION CORPORATION, A CORPORATION OF DELAWARE

REFRIGERATION SYSTEM AND METHOD

Application filed March 25, 1926. Serial No. 97,393.

My invention relates to improvements in the art of refrigeration. The object of my invention is generally to provide for a more cleanly, economical, and efficient means of refrigeration than obtains at present. In the art of refrigeration ice is, so far as known at present, the cheapest refrigerant. The use of it, however, is objectionable in many ways. It is difficult to cut the pieces to fit the requirements of a refrigerator without waste and without a good deal of messiness. In using ice for household purposes this feature is especially objectionable, as it tends to so much confusion and wetness around the refrigerator. In use a serious objection is that it has to be renewed so often, and when the ice box is substantially full, the cooling effect is rapid and almost too intensive, but as the ice melts and the water runs away, the cooling surface becomes gradually reduced, and before the ice is melted and a new supply put in the refrigerator, the cooling effect is so low as to be ineffective and of practically no use. In my improved system, however, I obviate all these difficulties. I freeze the ice in a closed container, which can be placed in the refrigerator without the slightest mess or disturbance, and as the ice melts, the water is not drained away, but stays in the container so that the extent of the cooling surface is constant, and remains so until the ice is substantially all used or melted. Thus the cooling effect is regulated or controlled so that the temperature of the refrigerated space is substantially constant, and furthermore by reason of this control, the refrigerating effect lasts very much longer than where the melted ice runs to waste, with the result that the refrigerator has to be supplied to the refrigerator only at long intervals, which is a decided advantage in many ways, as will be apparent.

In carrying out this idea I also provide a refrigerator in which the circulation is advantageously promoted, and the warm air

constantly directed to the refrigerating containers so as to give up its heat rapidly and permit the cold air to descend to the preserving space of the refrigerator.

Reference is to be had to the accompanying drawings forming a part of this specification, in which similar reference characters indicate corresponding parts in all the views.

Figure 1 is a front elevation with most of the doors removed of a refrigerator organized in accordance with my improved system and method.

Figure 2 is a cross section on the line 2—2 of Figure 1.

Figure 3 is a front elevation of the refrigerator partly in section and with the refrigerant containers removed.

Figure 4 is a vertical section on the line 4—4 of Figure 3.

I have shown my system in connection with a refrigerator 10, which can be any cooling chamber, as for example, car, vault, household refrigerator or the like, and so far as its general construction is concerned it can be of any approved character, but should have the walls well insulated, and tight doors. I prefer in carrying out my system, to use a refrigerator of the type shown in my application for Letters Patent of the United States filed March 25, 1926, Serial No. 97,392.

As illustrated, the refrigerator 10 has in the top space 11 corresponding to that of the ordinary ice box, in which are fitted casings 12 which are open only in front and which fit nicely in the space 11, extending from front to rear, but leaving a flue 13 between the outer sides of the casings 12 and the wall of the refrigerator, and leaving also a continuation 14 of said flues above the casings 12. Obviously there can be any desired number of these casings. I prefer to use between the casings a refrigerant container 15 which is removed only at long intervals, and which has openings horizontally therethrough to receive removable drawers 17 which can con-

tain water or other liquid to be frozen. In the door 19 in front of the container 15 are removable plugs 18 which come opposite the drawers 17, and which are removed to permit 5 the removal of the drawers. The door 19 can be of any approved type. In the bottom of each casing 12 are slots 20 which can be used to promote circulation between the containers therein, which will be presently referred to, and these slots may be opened or closed by the damper or slide plate 21 beneath each casing, this plate having a slot 22 therein to register with the slots 20. The dampers or slide plates can be moved to open 10 or close the slots referred to, in any convenient way. I have shown two dampers 21 connected by a rod 23 which has an operative connection by means of the crank 24 with a transverse shaft 25 extending forward 15 through the refrigerator and provided with a suitable handle 26.

I use closed containers 27 for the refrigerant, which can be frozen water or other liquid having a lower freezing point than 25 water, and these fit nicely in the casing 12 but so as to leave a little space between the containers and between the sides and tops of the containers and the adjacent casing wall. The space between the containers 27 in 30 each casing registers with the slots 20 in the casing bottoms. I find it convenient for most purposes to have the casings 12 arranged to receive two containers, but obviously they may be made to contain any number of 35 containers. The containers are easily removable, and have handles 27' on the front ends to facilitate such removal.

It will be noticed by reference to Figure 2 that the arrangement shown makes a down-draft flue 28 between the casings 12 and the container 15, but if the container were not used, the draft flue would of course be between the two casings. Below the containers I place a division plate 29 which is dish 45 shape, and which is of such a width as to leave air flues 30 between its side edges and the adjacent walls of the refrigerator 10. At the center the division plate is open as at 50 21 so as to connect with the flue 32 which is formed between the preserving or refrigerating casings 33, these being placed side by side in the lower part of the refrigerator, and serving the ordinary purpose of carrying 55 the materials to be stored in a refrigerator. These chambers 33 have openings 33' through the top and beneath the division plate 29, and openings 34 through their inner walls near the bottom. I have shown also 60 a drip pipe 35 below the flue 32, so that any small amount of water which may arise by reason of precipitation can drain off, but there is no drip from melting ice, as the ice 65 water is held sealed in the container 27 or 15, as the case may be. The chambers 33 can be

provided with any preferred arrangement of shelves 36.

In Figure 2 I have shown the upper part of the refrigerator provided with doors 37, and the lower part may also be provided with 70 these or other doors, and in fact any desired door arrangement for the refrigerator, and any general design for the refrigerator itself, can be used without affecting the invention.

It will be seen that when the containers 27 are placed in the refrigerator, the warmer air from the lower part of the refrigerator will rise from the openings 33', pass upward through the flues 30 and 13, thence transversely through the flues 14, thence downward through the flues 28, and finally down through the flues 32 and openings 34 to the chambers 33 without coming in contact with the refrigerant containers 27 but only with 80 the wall of the casing 12, and thus the ice in 85 the container is not too rapidly melted. Thus the cold air is constantly displacing the warmer air of the chamber 33, which must of necessity pass out through the openings 33', and a constant positive circulation is maintained. It will further be noticed that the 90 cooling surface, that is the surface of the casings 12 and containers 27, remains constant as the ice melts, and as a result a very even temperature is maintained in the refrigerator until the ice is almost entirely consumed. For this reason I find that in refrigerators of ordinary capacity, renewals of the 95 containers are not necessary more than twice a week, and seldom more than once a week, 100 and it will be further observed that the renewal of the containers is a very simple matter, as they are simply taken from the refrigerator, cold ones substituted, and the removed ones again chilled.

In practice the slots 20 can be kept closed until the ice is pretty well melted, after which they may be opened, and a down draft will occur between the containers 27 and through the flue 32 and chambers 33.

I claim:—

1. A refrigerator having a cooling chamber and a preserving part, a closed container having a frozen refrigerant therein in said cooling chamber, means directing a circulation of air through the preserving part of the refrigerator and in proximity to but out of contact with the refrigerant container, and means permitting a portion only of the air thus circulating to circulate in and out of the cooling chamber and thus come into direct contact with the refrigerant container.

2. The improvement in the art of refrigeration which comprises placing in a refrigerator a frozen refrigerant in a closed container whereby the melted liquid of the refrigerant is held from wasting and a constant cooling surface maintained, and regulating the circulation of air in proximity to but out of contact with the refrigerant container, and

through the containing and preserving part of the refrigerator.

3. A refrigerating system comprising a refrigerator having preserving or material containing space therein, and easily removable closed containers containing frozen refrigerant together with means for promoting an air circulation through the preserving part of the refrigerator and in proximity to but out of contact with the containers.

4. A system of refrigeration comprising in its organization a refrigerator having a preserving chamber, a refrigerant casing, a removable refrigerant container fitting loosely in the casing, and circulation flues arranged to circulate air from the preserving chamber around the casing but out of contact with the refrigerant container a means operable to permit air to circulate from the preserving chamber through the casing in direct contact with the refrigerant container when the temperature in the container drops to a substantially predetermined temperature.

5. A system of refrigeration comprising in its organization a refrigerator having a preserving chamber and a refrigerating space thereabove, a pair of refrigerating casings in said space, spaced from the sides and top thereof and defining a flue therebetween for the circulation of air, closed containers having a frozen refrigerant therein removably mounted in said casing in spaced relation, draft flues in said casing, a means for opening said draft flues to permit independent circulation of air through said casings in direct contact with said containers.

6. A system of refrigeration comprising in its organization a refrigerator having a preserving chamber and a refrigerating space thereabove, a pair of refrigerating casings in said space, spaced from the sides and top thereof, means providing for continuous circulation of air from said preserving chamber through said refrigerating space in contact with said refrigerating casings, closed containers having a frozen refrigerant therein removably mounted in said casings in spaced relationship, and means for controlling the circulation of air through said casings to permit independent circulation of air in said casings in direct contact with said containers, said means being adapted to be operated when the temperature of the refrigerant in said containers drops to a predetermined temperature.

7. A system of refrigeration comprising in its organization a refrigerator having a preserving chamber and a refrigerating space thereabove, a pair of refrigerating casings in said space, spaced from the sides and top thereof, and defining a flue therebetween for the circulation of air, closed containers having a frozen refrigerant therein removably mounted in said casing in spaced relation, draft flues in said casing, a means for

opening said draft flues to permit independent circulation of air through said casings in direct contact with said containers and additional refrigerant containers mounted in the flue between said refrigerating casings, said last mentioned containers having trays therein adapted to receive a liquid to be frozen.

In testimony whereof, I have signed my name to this specification this 17th day of March, 1926.

WALTER LIGHT BODMAN.
